(57) **CLAIM**
The ornamental design for a 3 in 1 rearview mirror assembly, as shown.

DESCRIPTION

FIG. 1 is an isometric perspective view of a 3 in 1 rearview mirror assembly in accordance with the present design;

FIG. 2 is a front view thereof;

FIG. 3 is a back view thereof;

FIG. 4 is a side view thereof;

FIG. 5 is a top view thereof; and,

FIG. 6 is a bottom view thereof.
